UNITED STATES PATENT OFFICE.

PAUL J. TIMBERLAKE, OF JACKSON, MICHIGAN.

HOLDER FOR ELECTRIC LIGHTS AND OTHER PURPOSES.

1,402,685.

Specification of Letters Patent.

Patented Jan. 3, 1922.

Application filed January 2, 1920. Serial No. 348,813.

To all whom it may concern:

Be it known that I, PAUL J. TIMBERLAKE, a citizen of the United States, residing at Jackson, in the county of Jackson and State 5 of Michigan, have invented certain new and useful Improvements in Holders for Electric Lights and other Purposes, of which the following is a specification.

In many homes are found handsome jars 10 and vases of ornamental pottery or glass that are of little or no practical use and which for that reason have in many cases been discarded. They are well adapted to serve as bases for ornamental lamps; and 15 my invention has for its object to produce a support or holder for an electric light fixture that may be easily applied to such a jar or vase and will securely hold the lamp in such manner that it may serve as the base 20 or standard for the lamp. While the holder I have invented is particularly adapted for the use just stated, it is not limited, in its useful applications, to that one use, but may be employed in a wide variety of situations where the holding parts for the lamp 25 or other article to be supported are adapted to enter a vessel of some sort, or like hollow article, and engage with the inner walls thereof.

30 In the accompanying drawings:—

Figure 1 is a sectional view illustrating one form of the holder applied to a jar that is shown in section.

Fig. 2 is a similar view to Fig. 1, illustrating a different embodiment of the invention in several particulars.

Fig. 3 is a top plan view of the form of holding means shown in Fig. 2.

Fig. 4 is a view of another form of my 40 invention, in elevation and section.

Fig. 5 is a perspective view, detached, of still another embodiment of my invention.

Fig. 6 is a view, partly in elevation and partly in section, illustrating features of 45 invention not shown in any other views.

Fig. 7 is a top plan view of the holding means shown in Fig. 6.

Fig. 8 is a view, in elevation and section, illustrating another form of the invention.

50 Fig. 9 is a top plan view of holding devices for engaging with the standard different from those shown in the views already described.

Fig. 10 is a perspective view of holding 55 devices of the general character of those

shown in Fig. 9 but differing therefrom in details of construction.

In the drawings A represents a jar or vase, which is typical of a hollow standard with which the support constituting my invention may be used. Such support has been devised with especial reference to use in connection with jars and vases such as shown, which have comparatively wide open mouths and are constructed with inflaring 60 upper ends. However, the invention may be used in connection with other articles, and the vase is sometimes herein referred to by the generic expression—a hollow standard.

B designates a cover for the open end of the jar, and C designates parts of an electric light connection, including the lamp socket and the flexible cord. The latter may enter the jar from above, passing 70 through the cover B, as represented in some of the views, or from below, provided the hollow standard has an opening in its lower portion for that purpose, as represented in Fig. 6.

Referring now particularly to Fig. 1, which represents the form of the invention which I prefer on account of the cheapness and simplicity of its construction. 2, represents a long screw passing through an opening 3 in the cover B, against the outer face of which the head of the screw rests, while its screw-threaded portion has engagement with an adjustable plate 4 within the jar.

5, 5, represent a pair of holding members 90 adapted to engage with the interior surface of the jar and thus retain the lamp holder in place, which holder includes in the particular embodiment of the invention here shown the cover B and the electric 95 connection C. The holding members 5 have heads 10 shaped to engage with the interior walls of the jar being preferably resilient and covered with rubber tubing 11 to prevent the heads from slipping when in engagement with the wall, and screw-threaded stems 6, which latter are seated in extensions 7 of the adjustable plate 4. These extensions, in the form of the invention being described, are separate from the plate 4 but 105 united thereto by hinges 8. A contractile spring 9 unites the hinged extensions 7, tending to draw their free ends toward each other, and in so doing to force the heads of the holding members 5 outward and into 110

engagement with the interior walls of the jar.

The manner of using a holder such as described is as follows: The holding members 5 are screwed into the extensions 7 of the adjustable plate to the proper extent to accommodate them to the size of the jar or hollow standard with which they are to be used. Likewise, the screw 2 is adjusted to move the plate 4 to the position best suited for the shape and size of jar being employed as the lamp standard. The holding parts 5 are then moved toward each other sufficiently far to permit them to pass through the mouth of the jar and into the interior thereof, the spring 9 being distended to permit these movements. After passing the contracted portion of the jar and entering the interior thereof the parts are brought to the position indicated in Fig. 1, the spring 9 forcing the holding arms 5 outwards into operative, gripping positions. The screw 2 is now adjusted to lift the plate 4, and the parts that it carries, thus bringing the resilient ends 10 of the holding arms 5 into close engagement with the inner walls of the jar. The desired pressure for causing working engagement of these arms may be effected by means of the adjusting screw, and the resilient nature of the arms, as well as the elastic cover 11 thereof, prevents them from being brought into such forcible engagement with the jar as might tend to break it. By the means shown the lamp support may be easily applied to and securely held upon the jar, and thus the latter converted into part of an ornamental lamp.

In Figs. 2 and 3 I have shown a different embodiment of the invention. In this view the adjusting screw 2 instead of being free to turn relative to the cover 4 is seated in a block 20 on the underside of the cover B. The screw-threaded portion of the screw passes through an adjustable plate 4', the extensions 7' of which are integral therewith. The interior holding members, in this form of my invention, are designated 5' and consist of looped pieces of wire shaped to form the wall-engaging heads 10', which are shown as covered with rubber tubing 11. The free ends of the holding arms 5' are brought relatively close together and formed into hooks 13 adapted to pass through openings 12 in the adjustable plate 4', this arrangement constituting a hinge connection between each arm and the adjustable plate. The free end of each holding arm is held outwardly, so as to be forced into engagement with the interior wall of the jar 8 by a spring 9'.

It will be seen that the holding arms 5' of this form of my invention have hinge connections with the adjustable plate 4' which are direct, instead of being intermediate as represented in the Fig. 1 construc-

tion, where the extensions 7 with which the arms engage are structurally separate from the plate 4 and are united thereto by hinges.

The oppositely extending arms that have pivotal connection with the screw-threaded plate or nut on the adjusting screw 2 form a toggle, the free ends of which contact directly by end thrust with the inner surfaces of the hollow standard A.

In the first described form of my invention the holding arms are bodily adjustable in their carrying supports and are also held in working position by the spring 9, whereas in the Fig. 2 construction the arms are not bodily adjustable but have a wider range of adjustment about their hinge connections with the plate 4 than is given the corresponding parts in the Fig. 1 construction. In order to move the plate 4' so as to bring the free ends of the holding arms 5' into forcible holding engagement with the interior walls of the jar, either the cap or cover B is turned relative to the jar A, if the electric cord be free, or the jar is turned relative to the cap, if the electric cord has been connected with the supply system, this being necessitated by the fact that the end of the screw which is seated in the block 20 is not accessible.

In Fig. 4 is shown a form of invention employing holding arms 5, such as shown in Fig. 1, but using a different form of adjustable plate, which in this view is designated 4''. This plate is formed of resilient metal with loop-shaped spring extensions 7'' in which the screw-threaded stems 6 of the holding arms 5 are seated. The resiliency of the arms 7'' constituting the extensions of the adjustable plate take the place of the hinge extensions 7 of Fig. 1, and the spring 9 uniting them.

In Fig. 5 is illustrated a form of holder somewhat like that in Fig. 2, but differing in that the holding arms 5' do not have hinge connection with the extensions 7''' of the adjustable plate 4'''. This plate is provided with a series of apertures 15 arranged in pairs and at different distances from the center of the plate, adapted to receive the hook-shaped ends 16 of the holding arms 5'. The arms of the holding elements are provided with collars 17 near their hooked ends to form stops adapted to rest on the upper surface of the plate 4''', as represented in the drawings. By inserting the hooked ends of the holding arms in one or another set of openings 15 they may be adjusted to suit the size of the jar with which the holder is used. The arms will rock sufficiently in the apertures 15 to permit the holding arms to be moved toward each other to an extent to allow them to pass through the contracted mouth of the jar.

It will be noted that in each of the forms of my invention thus far described the hold-

ing arms, which may be in one form or another, extend outwardly from the central adjusting screw 2 and are adapted to have their ends brought into forcible engagement with the inner walls of the standard to effect the desired holding action, by adjustment of the screw. The holding means, comprising the two oppositely extending arms, are adjustable as a whole by the screw and are rigid, 10 in one direction at least, so as to resist movement as the ends of the arms are brought into engagement with the inner walls of the standard by the action of the screw. I am thus enabled to secure a very firm and satisfactory holding and securing action by the use of means of simple construction and operation.

While the holding arms are, as stated, rigid in one direction, they are nevertheless yielding in the opposite direction, to permit the holding parts to be readily passed through a contracted opening as has been described. This capability adds much to the ease with which the holder may be applied to 25 standards of the shapes shown in the drawings, that is, to vases or other articles having more or less contracted open ends.

The inner walls of the standard are sloping and the holding means are brought into 30 engagement therewith by bodily adjustment, as distinguished from adjustment of the individual arms about their pivots; and hence it is important that such holding means should be rigid as has been pointed out. The 35 word "rigid" is not employed in the absolute sense, because the nature of the material employed in making the holding arms is more or less resilient and would yield if sufficient force were applied thereto; but no great degree of force is required in using my holding 40 device and the holding parts act as though they were actually rigid under the pressures and forces to which they are subjected when properly used. In some forms of my invention, 45 that of Fig. 1 for instance, portions of the arms, such as the ends thereof, may be made resilient, but the functions of the device incident to the rigidity of the holding arms, as has been described, are retained, notwithstanding the arms are in part resilient. 50

In the form of invention shown in Figs. 6 and 7 the holding arms 5⁴ are formed of resilient wire looped very much as are the arms shown in Fig. 2 to form the outer jar- 55 engaging parts 10⁴. Their inner free ends are however coiled to constitute resilient loops 18 that form the spring elements holding the ends of the arms in working position. The free ends of the wires constituting the 60 holding arms are secured fast to the plate 4⁴, as by brazing or soldering. In this form of the invention the adjusting screw 2 is not used. In place thereof I employ a hollow screw 21 that engages with the plate 4⁴ and 65 is of a size to carry the lamp cord *c*, which

enters the jar B or other form of standard from below. The hollow screw 21 is seated in the cap B so as to be free to turn therein in order that the screw may be manipulated to adjust the plate 4⁴. A set screw 22 may 70 be used to hold the hollow screw in place after it has been adjusted.

In Fig. 8 is represented a form of holder in which the supporting plate 4⁵ and the resilient holding arms 5⁵ are integral and 75 formed from resilient sheet metal.

In Figs. 9 and 10 are shown forms of my invention having features in common. In these views the adjustable supporting plate is in the form of a circular disk 4⁶ having 80 screw threaded connection with a hollow screw 21 similar to the correspondingly designated screw shown in Fig. 6. From diametrically opposite points on the periphery of the adjustable plate 4⁶ extend studs or 85 arms 24 that constitute supports for the holding arms 5⁶. These studs or arms 24 are conveniently formed by securing a piece of wire to the under side of the plate 4⁶. In the form of invention shown in Fig. 9 the opposite holding arms 5⁶ are integral, being united at their inner ends by coils or loops 90 23 of the wire of which they are formed, such coils encircling the lateral projecting studs or arms 24 which constitute a supporting fulcrum for the arms. The wire of which the arms 5⁶ is formed being elastic the coils 23 act as springs that hold the outer ends of the arms in holding engagement with the standard. 100

In that form of invention shown in Fig. 10 the two arms, 5⁶ are separate. Each is formed with loops or coils 23' surrounding the supporting arms 24. The ends of the wire of which one of the arms is formed are continued beyond the coils 23' and formed into hooks 25 that engage with the side bars of the opposite holding arm as shown in the drawings. This arrangement maintains the arms in proper working position, permits them to have the necessary freedom of movement with reference to each other so that the whole may enter the contracted mouth of a standard and furnishes the desired springs for the article. 110 115

It will be seen that in the several views in which different forms of my invention are illustrated the parts that are similar to each other in function are given the same reference characters, although each form is distinguished from the other by the use of a different exponent. 120

It will be seen that in several of the forms of invention shown and described there are stops carried by the vertically movable supports for the holding arms of the device which stops operate to prevent such movements of the arms as would carry the outer ends thereof, which engage with the inner walls of the standard, outwardly and down- 125 130

wardly after they come to normal holding positions. Thus in the construction shown in Fig. 1 the hinged extensions 7 rest against the ends of the plate 4 when the arms are in their normal holding positions represented in the drawings; in the construction represented in Figs. 2 and 3 the upper outer edges of the openings through which the hooks 13 of the arms pass, constitute the stops for arms 10 resting and holding the arms in normal positions; while in the construction of Fig. 5 it is the under surfaces of the plate 4³ adjacent to the openings 15, with which engage the ends 16 of the holding arms that constitute these stops.

What I claim is:—

1. The combination with a holder for an article such as an electric lamp, of means for securing it to a hollow standard, comprising 20 arms adapted to enter the standard and to engage with the inner walls thereof and adjustable supporting carrier means for the arms from which they extend outwardly, the arms and supporting carrier comprising securing means that are rigid against pressures incident to their being brought into holding engagement with the walls of the standard, and means for adjusting bodily the securing means to bring the ends of the 30 holding arms into engagement with the walls of the standard.

2. The combination with a holder for an article such as an electric lamp, and a hollow standard for the holder having a contracted 35 mouth, of means for securing the holder to the standard, comprising arms adapted to enter the standard and engage with the inner walls thereof below the said mouth, the arms being freely movable in one direction 40 to permit them to approach each other as they pass through the mouth of the standard, but together constituting a device normally rigid as a whole against the pressures incident to the ends of the arms being 45 brought into engagement with the inner walls of the standard, and means extending into the standard for adjusting the holding arms bodily to bring the ends thereof into holding engagement with the walls of the 50 standard after the arms have been passed inside the standard.

3. The combination with a holder for an article such as an electric lamp and a hollow standard for the holder having a contracted mouth, of means for securing the holder to the standard, comprising an adjusting screw adapted to enter the holder, a carrying support mounted upon the screw and arranged to be adjusted thereby, arms 55 having hinge connections at their inner ends with the carrying support and their outer ends being adapted to engage with the inner walls of the standard below the mouth thereof, the arms being freely movable in one direction, by reason of the said hinge connec-

tions, to permit them to approach each other as they pass through the mouth of the standard, means for automatically restoring the arms to positions to engage with the inner walls of the standard after they have 70 entered the standard and passed beyond the contracted mouth thereof, and means for causing the arms to resist pressures incident to their ends being brought, by the action of the adjusting screw, into engagement 75 with the inner walls of the standard.

4. The combination with a holder for an article such as an electric lamp and a hollow standard therefor, of means for securing the holder to the standard, comprising arms 80 adapted to enter the standard and to engage with the inner walls thereof, means adapted to be operated from the outside of the standard for adjusting the holding means and moving them into holding engagement with 85 the inner walls of the standard, and other means by which the holding arms may be adjusted with reference to each other to suit the size and shape of the standard with 90 which they are to be used.

5. The combination with a holder for an article such as an electric lamp, and a hollow standard the inner walls of which are sloping, of means for securing the holder to the standard, comprising outwardly extending arms the ends of which are adapted to be moved into holding engagement with the sloping inner walls of the standard, and the arms being constructed to be rigid so as to resist movement relative to each other when such engagement takes place, and means adjustable from the outside of the standard 100 for supporting and carrying the arms and bodily moving them along right lines into engagement with the sloping walls of the 105 standard.

6. The combination with a jar having an open contracted mouth, and a cover for closing the mouth, adapted to support a lamp or similar article, of means for securing the 110 cover in place adapted to be located within the jar, comprising a centrally located supporting plate having hinged extensions, holding arms adapted to engage with the inner walls of the jar having screw-threaded engagement with the said hinged extensions 115 of the supporting plate whereby they may be adjusted bodily to suit the size of the standard with which they may be used, a spring uniting the hinged extensions for forcing the holder arms outward to engage with the jar, and a screw seated in the supporting plate and uniting it with the cover.

7. The combination of a hollow standard 125 the upper end of which is open, a cover for the standard arranged to carry an article such as an electric lamp, an adjusting screw supported by the cover and adapted to extend downward into the standard, a carrying support mounted on the screw and ver- 130

tically adjustable thereby, holding arms the outer ends of which are adapted to engage with the inner walls of the standard to secure the cover in place, their inner ends having pivotal connections with the said adjustable carrying support, which permit the arms to move in an upward direction, causing their outer ends to approach each other so they may pass through the open end of the standard to the interior thereof, and means for preventing the arms from moving downwardly beyond determined positions which they occupy when brought into engagement with the inner walls of the standard, the carrying support and holding arms being adjustable, as a unit, up and down by means of the aforesaid screw.

8. The combination of a hollow standard the upper end of which is open, a cover for the standard arranged to carry an article such as an electric lamp, an adjusting screw supported by the cover and adapted to extend downward into the standard, a carrying support mounted on the screw and vertically adjustable thereby, holding arms the outer ends of which are adapted to engage with the inner walls of the standard to secure the cover in place, their inner ends having piv-

otal connections with the said adjustable carrying support which permit the arms to move in an upward direction, causing their outer ends to approach each other so they may pass through the open end of the standard to the interior thereof, and stops carried by the supporting plate for arresting the outward and downward movements of the arms in proper holding positions.

9. In a device of the character set forth, a support adapted to apply upon the mouth of a vase or similar article, a screwthreaded rod secured to said support and extending into the interior of such vase, a nut on said rod, oppositely extended arms pivotally mounted on said nut, adapted to form a toggle and having their free ends adapted to contact directly by endwise thrust against the inner surfaces of such vase, cushions on said free arms, and a spring tending to straighten said toggle, whereby the rotation of said support turns said rod in said nut to straighten said toggle, engage said free ends firmly against the inner surfaces of such vase, and draw said support tightly to such mouth.

PAUL J. TIMBERLAKE.
